SLIDE LOOP

George Henry Elwell, New Haven, Conn., assignor
to Eastern Tool and Manufacturing Company,
Bloomfield, N. J., a corporation

Application November 18, 1943, Serial No. 510,752

2 Claims. (Cl. 24—170)

This invention relates to slide loops, the physical combination of a slide adapted to be secured to a strap for longitudinal adjustment thereon, and a button loop adapted to be clipped over a button carried by the garment to be thereby supported. The invention, however, particularly relates to an improvement of the slide portion of the device. In providing a slide portion of a slide loop for adjustable securingment upon a single strap, the more limited strap passage above and below an intermediate bar, dividing a rectangular open area of the slide into a pair of loops in a common plane, the better the grip of the device upon the strap threaded therein, but the more difficult the threading. The invention herein disclosed eliminates such difficulty by employing an intermediate bar which in cross-section substantially has different intersecting diameters so that, when positioned in the plane of the pair of loops, the strap passage open area is thereby reduced above and below the bar in contrast with the open area when the bar is revolved to a transverse position therein. By further employing an intermediate bar structure of companion loops providing spaced and relatively aligned sections permitting marginal insertion of a strap into threaded position therein, an additional contribution is made to the ease with which the improved slide loop may be secured upon a single strap.

The applicant is aware that the previous art discloses fixed wire companion loops longitudinally spaced, one from the other, and together comprising aligned sections of an intermediate bar structure in a vertical plane and integrally extending from both sides of a rectangular wire strap loop also in said plane. The applicant is also aware that the previous art discloses a movable intermediate bar provided with humps and extending across a sheet body member having perforations with which the humps are intended to register, the bar being movable alternatively to position said humps intersecting the plane of the body member and within the perforations to provide a strap-binding element, but in a parallel plane to that of the body member to release the strap. While the invention discloses herein relatively aligned intermediate bar sections of longitudinally spaced companion loops, the intermediate bar structure employed produces a new result in that when the bar is positioned in the plane of the body member the inserted strap is thereby secured and when the bar is positioned transversely to the plane of the body member, the strap is released.

With reference to the accompanying drawing, the Figure 1 illustrates a rear view of the device in which the intermediate bar structure is positioned relative to the body member in a transverse plane thereto; Figure 2 is an enlarged sectional view of the device on the line 2—2 of the Figure 1, the dotted outline of a strap being shown looped loosely around the companion loops during the process of securing the device upon a strap; Figure 3 illustrates a face view of the device in which the companion loops are shown positioned substantially in the plane of the body member; Figure 4 is an enlarged sectional view of the device on the line 4—4 of Figure 3, the dotted outline of a strap being shown looped snugly around the companion loops and wedged against teeth of the sheet-stock loop, the companion loops being locked in said position; and the Figure 5 illustrates a side view of the device.

Attention being called more particularly to the accompanying drawing, the numeral 1 designates the sheet-stock body part of the device having the strap loop 2 through its upper portion and the button 3 in the lower portion. The teeth 4 are provided by the sheet-stock at the upper boundary of, and projecting into, the strap loop 2, and the marginal edge 5 of the sheet-stock body 1 is rounded rearwardly to reinforce the body 1 and to improve its facial appearance. The rounded edge at the top of the body 1 is cupped over rearwardly sufficiently to provide a catch 10 for a purpose to be explained. The bearings 6 and 7 are formed in the sheet-stock body at the sides 8 and 9 of the strap loop 2.

A wire member comprising a one-piece formation having the upper bar 20, side bars 21 and 22, and companion loops 23 and 24 substantially parallel with, and in the plane of, the upper bar 20, each extending from a side bar 21 or 22, respectively, relatively spaced and longitudinally aligned within the space 25 therebetween, the terminals 26 and 27 of the wire extending outwardly in opposite directions and inserted within the bearings 6 and 7, respectively, for a revolving movement therein.

To mount and secure the device upon a strap S, the revolvable wire member is best positioned as illustrated by the Figure 2, thereby placing the companion loops 23 and 24 in a plane substantially at right angles to that of the sheet-stock body member, such positioning of the companion loops 23 and 24 making available a greater unobstructed open area of the strap loop 2 within 55 which to enter the strap S. With the strap S

held at the rear of the device and generously looped, as at S' in the Figure 2, the strap thus looped is best entered—one marginal portion at a time—through the space 25 between the companion loops 23 and 24 thus inserting, for instance, a marginal portion around the loop 23 and then the other marginal portion around the loop 24. The entire loop S' may then be drawn tightly around both of the loops 23 and 24 and, with the upper bar 20 lifted to a position within the plane of the sheet-stock body part 1 and caught under the catch 10, the companion loops 23 and 24 are thereby locked within said plane wherein they are to occupy such a substantial portion of the area of the strap loop 2, especially adjacent the line of teeth 4, that the portion S' of the strap S covering the companion loops 23 and 24 is brought directly into contact with the teeth 4 and thereby positively held against sliding movement of the device upon the strap. The 10 teeth 4 may be omitted if desired, they being included only as an added means of securement; the more or less abrupt off-set of the strap S threaded within the device being sufficient to another the device. The bar 20, held within the catch 10, is necessary especially to maintain the strap binding position of the companion loops 23 and 24 within the plane of the sheet-stock body member 1 when the strap portion above the device is not taut, such as when being laundered, but in use the taut strap is sufficient to maintain the bar 20 in vertical position.

To readjust the slide loop to a different position upon the strap S, the upper bar 20 is released from its vertical position to position the companion loops 23 and 24 sufficiently out of the plane of the body part 1 thus permitting the strap S a sliding freedom through the device.

While the invention is illustrated as employing in place of the usual intermediate bar companion wire loops 23 and 24 relatively aligned and spaced to admit marginally therebetween a strap thus placed around the wire loops, yet an unbroken intermediate bar extending entirely across the rectangular open area within the body portion of

the device and in cross-section having different intersection diameters as herein above explained, may be used to a great advantage with the exception that the threading of a strap into the device thus formed must be done in a manner common to the art when the intermediate bar is positioned in a plane transverse to that of the body member 1.

I claim:

1. A slide loop comprising a sheet-stock body member having an upper bar, side bars and a lower bar within which there is confined a rectangular opening through said member; bearings provided by the body member at said side bars upon opposite sides of said opening; a one-piece movable wire member of which the wire terminals are revolvably carried within said bearings, the wire member having an upper bar and side bars, the latter, together with said terminals, carrying spacedly aligned looped wire portions providing flat intermediate bar sections each projecting toward one another across said opening and lying in one revolved position with the wire of said loops adjacent upper and lower bars of said opening and, in another revolved position presenting said looped sections in a transverse relation to said opening, said positions decreasing and increasing within said opening the passage therethrough above and below said intermediate bar sections.

2. A slide loop comprising a sheet-stock body member having an upper bar, side bars and a lower bar defining a rectangular opening through said body member; bearings provided by the body member at opposite side of said opening; an intermediate bar member formed in a flat plane and extending substantially across said opening, said bar member having terminals by which it is revolvably carried within said bearings to position said intermediate bar substantially within said opening or in a plane transverse thereto, said positions decreasing or increasing within said opening the passage therethrough both above and below said intermediate bar.

GEORGE HENRY ELWELL.
